UNITED STATES PATENT OFFICE.

EDWARD J. VON PEIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

KEYBOARD MECHANISM FOR CASH-REGISTERS.

1,242,280.

Specification of Letters Patent.

Patented Oct. 9, 1917.

Application filed March 11, 1915. Serial No. 13,621.

To all whom it may concern:

Be it known that I, EDWARD J. VON PEIN, a citizen of the United States, residing at Dayton, in the county of Montgomery and State of Ohio, have invented certain new and useful Improvements in Keyboard Mechanism for Cash-Registers, of which I declare the following to be a full, clear, and exact description.

10 This invention relates to accounting machines and the like and more particularly to the control of the differential mechanism thereof.

In the illustrative form of embodiment disclosed herein the invention is shown applied to the well known type of machine shown and described in Letters Patent of the United States, No. 580,378, issued April 13, 1897, to Cleal and Reinhard. Although 15 it is shown applied to this type of machine, it is obvious that the invention may be employed in similar types of machines included in the same general class, the machines of this class being provided with depressible 20 keys to control the differential mechanism of the machine. In machines of this general class, it is usual to provide one bank of keys for each denomination represented in the machine; that is, one bank for each differential 25 unit controlling an accounting element.

The principal object of the present invention is to provide a keyboard and differential mechanism for cash registers or analogous machines by means of which a single bank 30 of keys may be employed to control either similarly or differentially a plurality of actuating mechanisms at the same time.

In key controlled cash registers and analogous machines adapted to the entry of 35 individual items, it is customary to provide a separate bank of keys for each denominational actuator, each actuator being controlled independently by its appropriate bank of keys.

40 By the employment of the present invention in machines of that type one bank of keys may be employed to control the actuators or differential mechanism appropriate to two denominational orders, thus reducing 45 the space required by two banks of keys.

In other types of machines constructed 50 for computing the difference between two given amounts such as in subtracting ma-

chines or change computing machines, or in 55 machines adapted to record two associated amounts such as cost and selling prices or stock number or quantity and selling price or amount tendered and amount of sale, separate banks of keys are provided for 60 recording the separate amounts.

By the employment of the present invention in machines of that type, one bank of keys such as shown in the present application may be provided for each denominational order and will thus be adapted to 65 control two actuators of that order, one for one of the given amounts and the other for the other of the given amounts. In such a use both amounts are set up on the same key 70 banks. This it will readily be seen, will eliminate the necessity of providing separate banks of keys for separate amounts.

It is thought that the present invention is 75 the first in the art to provide a machine employing denominational banks of keys so constructed as to render each bank capable of controlling a plurality of differential mechanisms.

It is further thought that this invention is 80 the first in the art to provide a single bank of keys controlling a plurality of actuators, said keys being capable of operation in groups operable in any order and determining by their order of operation the actuator 85 to be controlled by each key.

It may, therefore, be briefly stated that the principal object of this invention was to construct the key banks so that the keys of 90 each bank are capable of performing the functions formerly accomplished by two banks of keys. It is obvious that the employment of one bank of keys instead of two requires less space and greatly reduces the 95 cost of construction.

It was an incidental object of this invention to construct the key banks so that a key in a bank is depressed but once when, in the amount to be entered in the machine, the digits in the two denominations represented 100 by the bank are the same.

With these and incidental objects in view, the invention consists in certain novel features of construction and combinations of parts, the essential elements of which are set 105 forth in appended claims, and a preferred form of embodiment of which is hereinafter

described with reference to the drawings which accompany and form part of the specification.

Of said drawings:

6 Fig. 1 is a transverse vertical section through the machine being taken along the left side of a key bank forming the subject matter of the present invention.

10 Fig. 2 shows detail views of the latch mechanism for the tens differential mechanism.

15 Fig. 3 is a transverse vertical section through the machine being taken along the right side of the supporting frame shown in Fig. 1.

20 Fig. 4 is a detail view of the detent plate operated by manual depression of the keys.

25 Fig. 5 is a detail view of the combined depressing and detent plate operated by the main operating mechanism under the control of the keys.

30 Fig. 6 is a partial detail view of the key frame with but two of the keys shown.

35 Fig. 7 is a detail front view of the indicating and totalizing mechanisms controlled by the bank of keys shown in Figs. 1 and 3.

40 Fig. 8 is a detail side view of the mechanism for coupling the totalizing wheels to the differential means.

45 Fig. 9 is a detail sectional view taken through the bank of keys. The section is taken along the lower side of the key shown.

50 In the above described drawings only the units and tens key bank is shown, as the banks of higher orders are duplicates and the description of one bank is considered sufficient to the understanding of the invention. It is obvious, of course, that one or more of the key banks constructed according to the present invention may be used, if desired, in a machine having a number of ordinary key banks each of which represents but one denomination. It is also obvious that a bank of keys, such as shown, may be provided for each denomination and each of the two actuators be assigned to different items so as to permit of two amounts being registered on a single set of keys at the same time, such as "cost" and "selling" prices or amounts of "tender" and "sale."

55 In the preferred form of embodiment disclosed herein the keys are depressible to three different positions which for the sake of convenience may be called the inner, intermediate and outer positions. If but one key in the bank is depressed it is arrested in its intermediate position, and controls both the units and tens differential mechanisms, these two mechanisms in such cases being moved to the same extent. If two keys are depressed in succession, however, the first key is arrested in the intermediate position and the second key is arrested in its outer position, and then upon operation 60 of the machine, the first depressed key is

automatically depressed from its intermediate to its inner position. When two keys are depressed the first always controls the tens differential mechanism and the second controls the units differential mechanism. 70 To control the extents of depression of the keys, two detents are provided. One of these detents is employed to retain a single depressed key in its intermediate depressed position and to retain the second of two depressed keys in its outer depressed position, while the other combined depressing and detent plate is operated during the operation of the machine, if two keys are depressed, to effect movement of the first depressed of 75 the two keys from its intermediate to its inner position.

80 The two differential mechanisms controlled by the bank of keys are similar to that shown and described in the above mentioned Cleal and Reinhard patent. The units differential mechanism includes a pawl which engages the pin on a key in the intermediate or outer position of the latter while the tens differential mechanism carries a pawl which engages the pin on a key when the latter is in its intermediate or inner position. The engagement of these pawls limits the extent of movement of the differential mechanisms as fully described in 85 the Cleal and Reinhard patent.

Described in specific terms the keys 10 of a bank (Figs. 1, 3 and 6) are mounted in a key frame comprising two parallel plates 11 between which the keys are mounted. The key bank comprises ten keys arranged in numerical order, the bottom one being the "0" key and the uppermost one the "9" key. The key frame is rigidly mounted on a machine frame 12, the upper end of the key frame being mounted on the left hand side of the frame 12 as shown in Fig. 3, while the lower end of the key frame is supported in a rod 13 which passes through the lower forward portion of the frame 12, this portion 105 being constructed to pass between the plates 11. Each plate 11 has two rows of slots 13 and 14 and pins 15 and 16, which project from both sides of the keys, pass through the slots 13 and 14 respectively in both 110 plates. Each key, as shown in Figs. 1 and 6, carries an apertured lug 17, through the aperture of which the upper end of a corresponding rod 18 projects. The inner enlarged ends of the rods 18 have recesses 115 which engage over pins 19 projecting from one of the plates 11. Springs are coiled about the rods 18 and serve normally to retain the keys in undepressed position and to return the keys when depressed to such position during the operation of the machine, as is well known in the art.

120 A detent 22 (Figs. 1 and 4) comprises a plate 23 fast on the outer ends of the two arms of a lever 24, which is loosely mounted 130

on a rock shaft 25, supported by the frames of the machine. A second detent 26 (Figs. 3 and 5) comprises a plate 27 mounted on the outer ends of the arms of a lever 28 also loosely mounted on the shaft 25. The plate 23 of detent 22 is provided with two series of grooves 30 and 31, there being one groove in each series for each key. The detent plate 23 is normally in such position that when a key 10 is depressed the left hand end of the pin 15 on the key moves into its corresponding groove 30. The grooves 30 are so constructed that when a key is depressed it rocks the detent 22 counter clockwise about one-half of its full extent of movement, against the action of a spring 32 (Fig. 1), which is connected at one end to a rearwardly and downwardly extending arm 33 of the detent 22 and at its opposite end to a rod between the machine frames 12. A retaining bar 35 (Fig. 1) for holding the detent in moved position, is forked at its rear end over the shaft 25 and at its forward end is provided with a slot 36 through which a pin on the key frame passes to guide the bar in its reciprocation. The retaining bar 35 (Figs. 1 and 4) has three shoulders 37 on the lowest one of which the lower end of the detent plate 23 normally rests. When the detent 22 is moved, in the manner above described, its lower end is elevated to an extent sufficient to permit a spring 38 to move the retaining bar 35 rearwardly (to the left in Fig. 1) to carry the middle or next higher shoulder 37 under the lower end of the detent plate 23 and thereby retain the detent 22 in its moved position. As best seen in Fig. 4, the middle shoulder 37 is inclined downwardly and rearward so that as the retaining bar moves rearwardly the shoulder raises the detent 22 slightly further than it was raised by the depression of the key. When the detent 22 is moved to the position just described, the pin 15 on the depressed key is relative to its groove in the position shown in full lines and indicated by the reference numeral 34 in Fig. 4.

It can be seen that as the retaining bar 35 retains the detent 22 in its moved position the groove 30 coöperating with the pin 15 on the depressed key retains the key in this position, the detent 22 is raised slightly further by the middle shoulder 37 on the retaining bar 35, as above described, so that the pin on the key, when the operator removes his finger, engages the side of the groove just below the lower inclined edge of the groove for the purpose of insuring that the pin will be retained in its exact position, which might not be true because of wear or not sufficiently fine adjustment of the parts if the pin engaged the inclined edge of the groove when the operator removes his finger.

If but one key is depressed, it is retained

in the position described above during the operation of the machine but if two keys are depressed in succession, the first depressed key is moved from the intermediate position, above described, to its inner position during the operation of the machine, as will be described later.

The movement of the detent 22 by the depression of the first of two depressed keys raises the grooves 31 so that when the second key is depressed, its pin 15 enters its corresponding groove 31. These grooves 31 are so constructed that upon depression of the second key the detent 22 is given a second extent of movement whereupon the retaining bar 35 is moved still further rearwardly by the spring 38 to carry the uppermost shoulder 37 on the retaining bar under the lower end of the detent 22, thereby locking the detent in its fully elevated position. The uppermost shoulder 37 on the retaining bar 35 is also inclined downwardly and rearwardly so that the detent 22 is raised by the second rearward movement of the retaining bar slightly further than it was moved by the engagement of the pin on the key with the inclined portion of the groove 31. Each groove 31 has a set-off formed in its lower inner end so that when the detent 22 is raised slightly further by the uppermost shoulder 37 on the retaining bar 35 the lower side of the pin on the depressed key is seated in the set-off in its corresponding groove. In this position of the detent 22, the pin 15 on the second key depressed is retained relative to its groove 31 in the position indicated in Fig. 4 by the dotted lines marked 40 and the pin 15 on the first depressed key is relative to its groove 30 in the position indicated at 41 in section in Fig. 4.

During the operation of the machine the first depressed key is automatically depressed still further to its inner position, as above stated, by the following described mechanism, and in this position of the key its pin 15 is retained, relative to its groove 30, in the position indicated by the heavy lines marked 42 in Fig. 4.

The detent 22 carries a pin 43 (Fig. 1) which projects into a slot formed in an arm 44 fast on one end of a stub shaft 45 mounted in the key frame. As shown in Fig. 3, an arm 46 is fast on the opposite end of the shaft 45 and at its lower end the arm 46 carries a pin 47 which projects into a slot 39 formed in the forward upper end of a pitman 48. The pitman 48, at its forward lower end, is provided with a slot 49 surrounding a pin on the detent 26 and at its rear end the pitman is slotted to straddle a main drive shaft 51. A spring 52, which is secured at one end to a projection 53 on the pitman 48 and at its opposite end to the pin 47 on the arm 46 serves normally to re-

tain the pitman in its forward position shown in Fig. 3. When the first of two keys is depressed the pin 43 on the detent 22 is raised in the slot in the arm 44 about one-half the length of the slot, but this portion of the slot in which the pin 43 moves at this time is concentric to the shaft 25 so that the movement of the pin 43 does not rock the arm 44. When the second key is depressed, however, the pin 43 is raised into engagement with the upper end of the slot in the arm 44 to rock the arm 44 and shaft 45 clockwise, as viewed in Fig. 1. In this manner the arm 46 is moved counter clockwise, as viewed in Fig. 3, to move the pitman 48 rearwardly.

The pitman 48 carries at its rear end a roller 55 which is normally in such position that a cam ridge 56 formed on the right hand face of a disk 57, rigid on the shaft 51, moves behind the roller 55 during the operation of the machine. The shaft 51 is rotated in the direction of the arrow in Fig. 3. The means for rotating this shaft is not shown in the drawings as such means is not necessary to the understanding of the drawings and it is obvious that any desired means, such as a crank handle, motor, or other means, may be employed for the purpose. When the pitman 48 is moved rearwardly upon the depression of the second of two depressed keys as above described the roller 55 is moved rearwardly and upon operation of the machine, the cam ridge 56 moves in front of the roller 55. During such operation the cam portion 58 of the ridge engages the roller 55 to move the pitman 48 still further rearwardly, the slot and pin connection 39 and 47 being provided to permit this second rearward movement of the pitman independently of the arm 46. When the pitman 48 is moved rearwardly by the second depressed key the forward end of the slot 49 in the pitman is moved into engagement with its pin on the detent 26 so that when the pitman is moved still further rearwardly during the operation of the machine the detent 26 is rocked clockwise as viewed in Fig. 3, about the shaft 25. The detent 26 is rocked in this way against the tension of its spring 59 which is connected at one end to a downwardly and rearwardly extending arm 60 of the detent and at its opposite end to the rod supported by the machine frame 12.

The plate 27 of the detent 26 (Figs. 3 and 5) is provided with camming and locking lugs or projections 62 on its left hand side there being one lug for each key. The detent is normally in such a position that the pin 15 on the first of two depressed keys passes between two lugs 62 to its intermediate position indicated by the full lines 31 in Figs. 4 and 5. The pin on the second depressed key, if two keys are depressed, is not

moved between the lugs as the key is not depressed to the same extent as the first key, the pin on the second key being in the position indicated by the dotted lines marked 40. It is obvious that when the detent 26 is operated, as above described, the inclined edge of the lug 62 under the pin 15 on the first depressed key engages this pin and thereby moves it to its inner position which position relative to the detents 22 and 26 is indicated by the heavy lines marked 42 in Figs. 4 and 5. It can be seen that the ends of the slots 30 in the detent 22 are radial with this shaft 25 to permit the further depression of the first depressed of two keys 80 the lug 62 then engaging the pin 15 of the first depressed key serving to retain the key in its inner position.

From the above described construction it can be seen that when a single key is depressed the detent 26 is not operated as the pitman 48 remains in normal position and therefore the key is retained in its intermediate position, during the operation of the machine. If a second key is depressed, however, it is retained in its outer position by its groove 31 formed in the detent 22, the pin 15 on the key at this time being relative to the groove 31 in the position indicated at 40 in Figs. 4 and 5. When the second key is depressed the detent 22 is raised to its uppermost position and in this position of the detent the pin 15 on the first depressed key is in the position in the slot 30 indicated at 41 in Fig. 4. As depression of the second key moves the pitman 48 rearwardly so that the latter is operated by the cam ridge 56 during the operation of the machine the detent 26 is raised to cause further depression of the first depressed key, the pin 15 on this key then being in the position indicated at 42 in Figs. 4 and 5.

For the purpose of preventing the detent 22 from being raised more than one-half of its full distance upon a violent or sudden depression of the first depressed key the grooves 30 are cut to form small stop projections 67, (Figs. 1 and 4.) It can be seen that if a key was depressed suddenly the movement imparted to the detent 22 might be sufficient to carry it further upward than it should be moved by the key so that the pin on the key would then be in the enlarged or radial end of the slot 30. The projections 67 however, prevent such movement of the detent as one of these projections would engage the pin 15 on the key, the pin at such time being in engagement with the side of the groove 30 above the projection 67. When the clerk or operator removes his finger from the key, it moves slightly outward under the influence of its spring so that its pin 15 is in the position indicated at 34 in Fig. 4 so that if a second key is depressed the projection 67 will pass 130

by the pin 15 so as to permit the latter to pass into the enlarged end of its groove 30.

The differential means controlled by the keys when in their different positions will 5 now be described.

Loosely mounted on the central shaft 25 is a tens actuating segment gear 70 (Figs. 1 and 7) and a units actuating segment gear 71 of like construction (Figs. 3 and 7).

- 10 Each of these segment gears meshes with a corresponding gear 72, which in turn meshes with a pinion 73 rigid with a corresponding indicator drum 74. The units gear 72 is rigidly mounted on a shaft 68 and the tens gear 15 is fast on a sleeve 76 and this shaft and sleeve at their left hand ends carry type wheels (not shown) in a manner well known in the art and fully described and shown in the aforesaid Cleal and Reinhard 20 patent. The tens segment gear 70 on its left hand side (Fig. 1) and the units segment gear 71 on its right hand side (Fig. 3) carry similar latch mechanisms. Each latch mechanism, which is similar in principle to that shown and described in the aforesaid Cleal and Reinhard patent, comprises a latch bar 77 mounted on links 78 pivoted to the corresponding actuating segment gear. Two driving segments 79, one 25 for each actuating segment gear, are rigidly mounted on the central shaft 25 and are adapted to be connected to the corresponding segment gears 70 and 71 by the latch bars 77. The shaft 25 and the driving segments 30 79 are rocked clockwise about 90 degrees, as viewed in Fig. 1, and then rocked counter-clockwise, as viewed in this figure, past normal position and finally moved clockwise again to normal position, by 35 means fully shown and described in the Cleal and Reinhard patent. Briefly, this means comprises an arm 80 (Fig. 3) fast on the shaft 25 and connected by a link 81 to a crank 82 fast on the main drive shaft 40 45 51. When the driving segments 79 are rocked clockwise (Fig. 1) from normal position their shoulders 83 are carried opposite projections on the rear ends of the latch bars 77 whereupon springs 84 move 55 60 the latch bars 77 rearwardly and at the same time a flange 88 on a rearwardly extending arm 85 on the tens driving segment 79 engages the segments 70 and 71 to move the latter to zero position if they are not already 65 70 75 in such position. The flange 88 on the arm 85 is sufficiently long to engage both the tens and units actuating segments, and each segment will be picked up by it at the instant the latch bar 77, of the segment so 80 85 90 picked up, moves to engage in its appropriate shoulder 83.

During the counter clockwise movement (Fig. 1) of the segments 70 and 71 with the driving segments 79, the latch bars 77 95 are drawn forwardly under the control of

the keys to disconnect the segment gears 70 and 71 from the driving segments.

To this end two levers 87, each of which is pivoted to the corresponding segment gear 70 or 71, are bifurcated at the upper 70 ends of their vertical arms to straddle pins on the latch bars 77. At the outer ends of their forwardly extending arms each lever pivotally carries a pawl 90. Springs 91 normally tend to rock the pawls 90 clockwise 75 as viewed in Fig. 1 and counter clockwise as viewed in Fig. 3 but movement of the units pawl 90 (Fig. 3) is prevented by the engagement of a projection 92 on the pawl with the circular rear edge of the detent 80 plate 27 and this movement of the tens pawl (Fig. 1) is prevented by the engagement of its projection 92 with the circular rear edge of the detent plate 23. The tens pawl 90 (Figs. 1 and 2) on its upper right 85 hand side is provided with a lug or projection 93 and the units pawl 90 (Fig. 3) on its left hand side carries a similar projection 93. The rear edge of the detent plate 27 is of greater radius than that of the detent plate 22 and therefore the radii of the arcs described by the lugs 93 on the pawls 90 are different. For the sake of clearness keys 10 and pins 15 and 16 have been shown in their three moved positions in the three 90 lower pairs of slots 13 and 14 in plate 11 in Fig. 6 and reference may be had to that view for a fuller understanding of the same.

When but one key is depressed in the key bank, its pin 15 during the operation of the 100 machine remains in its intermediate position and in this position the pin 16 is in the path of movement of the lugs 93 on both the units and tens pawls 90. If two keys are depressed then upon the operation of the 105 machine the first depressed key is moved to the inner position by the detent 26, as already described, and in this position of the key its pin 16 is in the path of movement of the lug 93 on the tens pawl. The pin 15 on the second of two depressed keys is retained in its outer position and in this position the pin 16 of said key is in the path of movement of the lug 93 on the units pawl 90. When the lug 93 on a pawl 90 engages 110 a pin 16 on a depressed key the corresponding lever 87 is rocked to move the latch bar 77 forwardly and thereby disconnect its appropriate actuating segment gear 70 or 71 from its driving segment as is well known 115 in the art. Upon being drawn forwardly the forward end of the latch bars engage in notches 96 formed in the inner edges of the plates 11 of the key frame. It is obvious, of course, that the lugs 93 are inclined at 95 (Fig. 2) so that if the pin 16 on a depressed key is in the path of movement of the pawl 120 during clockwise movement (Fig. 1) of the actuating segment 70 or 71 to zero position the pawl 90 will be rocked counter clock- 125 130

wise (Fig. 1) to permit movement of the segment gear 70 or 71 to zero position the spring 91 serving to restore the pawl 90 to normal position as soon as it is past the pin 5 on the key. From the above description it can be seen that both actuating segment gears are moved differentially to the same extent when a single key is depressed and that the tens actuating segment gear is moved under the control of the first depressed key and the units actuating segment gear is moved under the control of the second depressed keys when two keys are depressed.

If zeros in the denominations represented by the key bank occur in an amount to be entered in the machine the "0" key, which is the lowest key in the bank, might be depressed, if desired, to disengage the latch bars 77 when the actuating segment gears are in zero position. However, in order to render the operation of the "0" key in such cases unnecessary and also in cases where the amount entered is less than the lowest denomination represented by a bank of keys the retaining bar 35 is provided with a vertical projection 97 (Fig. 1) having a nose adapted to engage over a nose on the lower end of the tens pawl 90 when the latter is in zero position and a bent bar 98 (Fig. 3) fast on the bar 35 and having a slot 971 through which a pin projects also has a projection 972 whose nose engages over the nose on the lower end of the units pawl 90 when the latter is in zero position. If no key in the bank is depressed the retaining bar 35 is retained in normal position and hence when the segment gears 70 and 71 are moved to zero position the pawls 90 are rocked counter clockwise (Fig. 1) by their engagement with the noses on the projections 97 until the noses on the pawls 90 pass the noses on the projections 97 whereupon the springs 91 return the pawls 90 to normal position relative to their carrying levers 87, at which time the noses on the projections 97 are over the noses on the pawls 90. It can be seen from this construction that if no key in the bank is depressed the projections 97 will prevent elevation of the pawls 90 and hence operate the latches 77 to disconnect the actuating segment gears from their driving segments 79. If a key is depressed, however, the retaining bar 35 is moved rearwardly, as above described, whereupon the noses on the projections 97 are carried out of normal operative position to permit movement of the actuating segment gears under the control of the depressed key or keys.

After the driving segments 79 have been moved to the position to which they carry the actuating segment gears when only a "9" key is depressed and before they complete their counter clockwise movement

(Fig. 1) the cam ridge 56 (Figs. 1 and 3) on the disk 57 passes out of engagement with the roller 55 on the pitman 48 whereupon the spring 52 draws the pitman 48 forwardly to the position to which it was moved upon depression of the second key to permit the detent 26 to be moved by its spring 59 to its normal position, whereupon the first depressed key is moved by its spring to its intermediate position and the second depressed key is moved to normal position. Then near the completion of the counter clockwise movement (Fig. 1) of the driving segments 79 a shoulder or projection 100 on the tens segment engages a pin 101 on the retaining bar 35 to move the latter forwardly to normal position whereupon the spring 32 moves the detent 22 to normal position to effect the release of the keys which are moved to normal undepressed positions by their springs.

It is customary in machines of the present type to provide means so that when a key is depressed in error it can be released before an operation of the machine is begun. This means comprises a shaft 103 extending longitudinally across the forward lower portion of the machine and bearing pins 104 (Fig. 1) each of which is normally out of engagement with a pin 105 on the forward end of the corresponding retaining bar 35. When it is desired to release an amount key before the operation of the machine is begun it is merely necessary to move a hand lever 106 (shown in Fig. 3 and omitted in Fig. 1) fast on the shaft 103, thereby rocking the shaft 103 clockwise (Fig. 3) so that the pins 104 engage the pins 105 and draw the operated retaining bars 35 forwardly to carry either their intermediate or uppermost shoulders 37 from out of engagement with the lower end of the detent plates 23 thereby permitting release of the amount keys.

While it is obvious that the mechanism hereinbefore described is capable of many other uses as set forth in the very early part of the specification, the invention is here embodied in a type in which each actuator is appropriate to a different denomination and the machine as illustrated is provided with a totalizer which is of the well known construction shown and described in the aforesaid Cleal and Reinhard patent. Referring to Figs. 7 and 8 a gear 108 is rigidly mounted on the shaft 68 on which is rigidly mounted the gear wheel 72 which meshes with the units actuator 71 and the pinion 73 on the units indicator drum. The gear 108 meshes with a pinion 109 to which is rigidly fastened a pinion 110. A companion pinion 111 is rigidly connected to the units totalizer wheel 112 by a short sleeve 125 surrounding a rod 121 and shown in dotted lines in Fig. 8. The gear 72 (Fig. 7) which

meshes with the pinion rigid with the tens indicating drum also meshes with a pinion 109 for the tens totalizer wheel 113. This pinion 109 for the tens totalizer wheel and a pinion 110 rigidly connected to the pinion 109 are loosely mounted on a sleeve 120 (Figs. 1 and 7) upon which the tens totalizer wheel 113 and its corresponding pinion 111 are fast. From the above described connections it can be seen that the differential movements of the actuating segment gears 70 and 71 are imparted to the corresponding pinions 110. In order to couple the pairs of pinions 110 and 111 together during the differential movement of the pinions 110 so that their movement will be imparted to the totalizer wheels, coupling pinions 114 (Figs. 7 and 8) are provided. These pinions are carried on arms 115 rigidly mounted on a shaft 116. The shaft 116 carries an arm 117 connected as shown in Fig. 8 to a pitman 118 which at its rear end is forked to straddle the main drive shaft 51. The pitman 118 also carries a roller 119 projecting in a cam groove formed in the face of a disk 129, fast on the drive shaft 51. This cam groove is so constructed as to rock the coupling pinions 114 into mesh with the companion pinions 110 and 111 so that the differential movement of the actuating segment gears 70 and 71 will be imparted to the totalizer wheels. The transfer mechanism which includes transfer pawls 123, carried by levers 124, is not fully shown or described herein, as such mechanism is well known in the art and its description is unnecessary to the understanding of the present invention.

It is thought that the above description is sufficient for a complete understanding of this invention and therefore a detailed description of its operation will not be given here. Briefly, however, it may be stated that the keys are depressible to three different positions. If but one key is depressed, it is retained in intermediate position during the operation of the machine and controls both the units and tens differential mechanisms and in such cases both of these differential mechanisms will be moved to the same extent. (Fig. 6.) If two keys are depressed the first depressed key is moved to inner position to control the tens differential mechanism and the second depressed key will be retained in outer position to control the units differential mechanism. If the same digits occur in both denominations but one key is depressed. For example, if the amount is 66 only the "6" key is depressed and both the units and tens indicator drums will indicate "6" at the end of the operation of the machine. If the digits in the two denominations are different the key representing the digit in the tens denomination is depressed first. For in-

stance, if 23 is to be registered the "2" key is first depressed and then the "3" key is depressed. If units only are to be entered into the machine the "0" key is first depressed and then the key corresponding to the digit is operated. For example, if 5 is to be entered in the machine the "0" key is first operated and then the "5" key is operated. On the other hand if 50 is to be entered into the machine the "5" key is first operated and then the "0" key is operated.

If the tens to be registered are greater than the units as in "92", the "9" key is first depressed to control the tens differential mechanism and then the "2" key to control the units differential mechanism.

It can, therefore, be seen from the above description that a key bank constructed according to the present invention is admirably adapted to accomplish the functions formerly obtained by two banks of arrestable keys, as any amount which could formerly be entered in the machine under the control of two key banks can now be entered in the machine under the control of a single key bank.

Although the present invention is shown as applied to amount keys, it is obvious that banks of clerks', special, transaction or waiters' keys may be constructed according to the present invention without departing from the scope of the present invention. It is, therefore, not intended to limit the present invention to any particular class of keys or to any particular form of differential mechanism.

While the form of mechanism herein shown and described is admirably adapted to fulfil the objects primarily stated, it is to be understood that it is not intended to confine the invention to the one form of embodiment shown and described herein, as it is susceptible of embodiment in various forms, all coming within the scope of the claims which follow.

What is claimed is:

1. In a machine of the class described, the combination with a main operating mechanism, of a bank of depressible and arrestable keys, the bank representing a plurality of denominations, a plurality of accounting elements one for each denomination represented by the bank of keys, and differential means for actuating one or more of the accounting elements upon operation of the machine and under the control of the bank of keys.

2. In a machine of the class described, the combination with a main operating mechanism, of a bank of depressible keys, arrestable in different positions, and representing a plurality of denominations, a plurality of accounting elements, one for each denomination represented by the bank of keys, and differential means for actuating

- one or more of the accounting elements upon operation of the machine and under the control of the keys in the different positions of the latter.
3. In a machine of the class described, the combination with a main operating mechanism, of a bank of manually depressible keys representing a plurality of denominations, each key being capable of being depressed but once preliminarily to the operation of the machine, accounting means representing the denominations corresponding to those represented by the bank of keys, and differential means for actuating the accounting means upon operation of the machine and under the control of said keys.
4. In a machine of the class described, the combination with a main operating mechanism, of a bank of depressible and arrestable keys representing a plurality of denominations, a plurality of accounting elements, one for each denomination represented by the bank of keys, and a plurality of differential mechanisms, one for each accounting element for actuating the latter under the control of said keys.
5. In a machine of the class described, the combination with a main operating mechanism, of a bank of keys representing a plurality of denominations and movable to different positions, means for retaining said keys in such positions, a plurality of accounting elements one for each denomination represented by the bank of keys, and a plurality of different mechanisms one for each accounting element and controlled by said keys in the different positions of the latter.
6. In a machine of the class described, the combination with a main operating mechanism, of a bank of manually depressible keys representing a plurality of denominations and capable of being depressed but once preliminarily to the operation of the machine, a plurality of accounting elements one for each denomination represented by said bank of keys, and differential mechanism for each accounting element and controlled by said keys upon operations of the machine.
7. In a machine of the class described, the combination with a main operating mechanism, of a plurality of accounting elements of different denominations, differential means for operating the accounting elements, driving means for the differential means, a plurality of latching mechanisms for coupling the differential and driving means, and a bank of depressible and arrestable keys, representing denominations corresponding to the accounting elements, for operating said latching mechanisms and thereby control the extents of movement of said differential means.
8. In a machine of the class described, the combination with a main operating mechanism, of a plurality of accounting elements of different denominations, differential means for operating the accounting elements, driving means for the differential means, a plurality of latching mechanisms for coupling the differential and driving means, and a bank of depressible keys representing denominations corresponding to the accounting elements and arrestable in different positions for operating said latching mechanisms and thereby control the extents of movement of said differential means.
9. In a machine of the class described, the combination with a main operating mechanism, of a plurality of accounting elements of different denominations, differential means for operating the accounting elements, driving means for the differential means, a plurality of latching mechanisms for coupling the differential and driving means, and a bank of depressible keys representing denominations corresponding to the accounting elements and arrestable in different positions for operating said latching mechanisms and thereby control the extents of movement of said differential means.
10. In a machine of the class described, the combination with a main operating mechanism, of a plurality of accounting elements, differential means therefor, driving means for the differential means, latch means for coupling the differential and driving means, and a bank of depressible keys representing denominations corresponding to the accounting elements and arrestable in different positions for operating said latch means and thereby control the differential movement of said differential means.
11. In a machine of the class described, the combination with a bank of keys representing a plurality of denominations, each key being depressible to different positions which correspond to the denominations which the key is to represent upon the particular operations, and differential means controlled by the keys in their different positions.
12. In a machine of the class described, the combination with a bank of depressible keys representing two denominations, the keys being depressible to one position to represent one denomination, to another position to represent the other denomination, and to a third position to represent both denominations, and differential means controlled by said keys in the different positions of the latter.
13. In a machine of the class described, the combination with a bank of keys representing a plurality of denominations, each key being depressible to different positions which positions correspond to the denominations which the key is to represent upon the particular operations thereof, and a plurality of differential mechanisms, one for each

- denomination represented by the keys, each differential mechanism being controlled by a key when the latter is in the position corresponding to the denomination represented by the particular differential mechanism. 5
14. In a machine of the class described, the combination with a bank of depressible keys representing two denominations, the keys being depressible to one position to represent one denomination, to another position to represent the other denomination and to a third position to represent both denominations, and two differential mechanisms both of which are controlled by a key 10 when the key is in the third mentioned position, while either is singly controlled by a key when the latter is in the position corresponding only to the denomination represented by the particular differential mechanism. 15
15. In a machine of the class described, the combination with a main operating mechanism, of two accounting elements, a differential mechanism for each accounting 20 element, a latch for each differential mechanism for coupling the differential mechanisms and the operating mechanism, and a bank of keys representing a plurality of denominations, each key being movable to different positions, both latches being tripped by a key when the latter is in one position, one latch being tripped by the key when the latter is in another position and the other latch being tripped by the key 25 when the latter is in a third position. 30
16. In a machine of the class described, the combination with a bank of keys representing different denominations, of two accounting elements, a differential mechanism 35 for each element both differential mechanisms being controlled by one key if but one key is depressed while each differential is controlled by a separate key if two keys are depressed. 40
17. In a machine of the class described, the combination with a bank of keys, representing different denominations, of two accounting elements, a differential mechanism for each element, driving means for the differential mechanisms, latches, one for each 45 differential mechanism for coupling the differential mechanism and driving means, and a bank of keys representing denominations corresponding to the accounting elements, both latches being tripped by one key if but one key is depressed, and each latch being tripped by a different key if two keys are depressed. 50
18. In a machine of the class described, 55 the combination with a bank of keys, representing different denominations, of two accounting elements, a differential mechanism for each element, both differential mechanisms being controlled by one key if but one key is depressed and a certain one
- of said differential mechanisms being controlled by the first key depressed and the other being controlled by the second key depressed if two keys are depressed. 60
19. In a machine of the class described, the combination with a bank of keys representing different denominations, of two accounting elements, a differential mechanism for each element, driving means for the differential mechanisms, latches, one for each differential mechanism for coupling the differential mechanisms and the driving means, and a bank of keys representing denominations corresponding to the accounting elements, both latches being tripped by one key if but one key is depressed, and a certain one of said latches being tripped by the first depressed key and the other latch being tripped by the second depressed key if two keys are depressed. 70
20. In a machine of the class described, the combination with a bank of keys, representing different denominations, of two accounting elements, a differential mechanism for each element both differential mechanisms being controlled by one key if but one key is depressed while each differential is controlled by a separate key if two keys are depressed, and means for preventing depression of more than two keys in the bank 75 to control an operation of the differential mechanisms. 80
21. In a machine of the class described, the combination with a bank of keys, representing different denominations, of two accounting elements, a differential mechanism for each element, both differential mechanisms being controlled by one key if but one key is depressed and a certain one of said differential mechanisms being controlled by the first key depressed and the other being controlled by the second key depressed if two keys are depressed, and means for preventing depression of more than two keys in the bank to control the differential mechanisms. 85
22. In a machine of the class described, the combination with a bank of keys, representing two different denominations and constructed so that one or two keys may be 90 depressed, of indicating means for indicating digits in both of said denominations, and differential means for actuating said indicating means under the control of said keys so that when one key is depressed the same digits in the two denominations will be indicated and if two keys are depressed different digits in the two denominations will be indicated. 95
23. In a machine of the class described, 100 the combination with a bank of keys manually depressible to differential positions, and means moved by the keys for controlling the extent of manual depression of said keys. 105
- 110
- 115
- 120
- 125
- 130

24. In a machine of the class described, the combination with a bank of keys, depressible to different positions, and detent means for arresting the keys in their different positions and for controlling the extents of depression of the keys. 65
25. In a machine of the class described, the combination with a main operating mechanism, of a bank of keys a plurality of which are capable of being depressed manually to different positions preliminarily to an operation of the machine, and detent means for arresting the keys in their different positions and for controlling the extents of manual depression of the keys. 70
26. In a machine of the class described, the combination with a main operating mechanism, of a bank of keys a plurality of which are capable of being depressed to different positions preliminarily to an operation of the machine, detent means for arresting the keys in their different positions and for controlling the extents of manual depression of the keys, and means for controlling further depression of one of said keys upon operation of the machine. 75
27. In a machine of the class described, the combination with a main operating mechanism, of a bank of keys a plurality of which are capable of being depressed to different positions preliminarily to an operation of the machine, detent means for arresting the keys in their different positions and for controlling the extents of manual depression of the keys, and means for disabling said detent means during the operation of the machine. 80
28. In a machine of the class described, the combination with a main operating mechanism, of a bank of keys one or two of which are capable of being depressed preliminarily to an operation of the machine, means for arresting the keys in their depressed positions, and means for causing upon operation of the machine further depression of one key if two keys have been depressed. 85
29. In a machine of the class described, the combination with a main operating mechanism, of a bank of keys one or two of which are capable of being depressed preliminarily to an operation of the machine, means for arresting the keys in their depressed positions, means for causing upon operation of the machine further depression of one key if two keys have been depressed, and means for disabling said arresting means during the operation of the machine. 90
30. In a machine of the class described, the combination with a main operating mechanism, of a bank of keys one or two of which are capable of being depressed preliminarily to the operation of the machine, means for arresting the keys in their depressed positions, and means for causing further depression of one of said depressed keys, the key further depressed being dependent upon the order of manual depression. 95
31. In a machine of the class described, the combination with a main operating mechanism, of a bank of keys one or two of which are capable of being depressed preliminarily to the operation of the machine, means for arresting the keys in their depressed positions, and normally inoperative means, rendered operative by the depression of two keys for causing further depression of one of the two depressed keys upon operation of the machine. 100
32. In a machine of the class described, the combination with a main operating mechanism, of a bank of keys one or two of which are capable of being depressed preliminarily to the operation of the machine, means for arresting the keys in their depressed positions, normally inoperative means, rendered operative by the depression of two keys for causing further depression of one of the two depressed keys upon operation of the machine, and means for disabling said arresting means during the operation of the machine. 105
33. In a machine of the class described, the combination with a main operating mechanism, of a bank of keys manually depressible to different positions any two of said keys being operable preliminarily to the operation of the machine, detent means having grooves coöperating with the keys for controlling the extent of depression of the keys the first of two depressed keys being depressed further than the second, and means operated by the main operating mechanism for depressing the first depressed key still further during the operation of the machine. 110
34. In a machine of the class described, the combination with a main operating mechanism, of a bank of keys one or two of which are capable of being depressed preliminarily to the operation of the machine, means for arresting the keys in their depressed positions, and means for causing upon operation of the machine further depression of the first depressed key if two keys are depressed. 115
35. In a machine of the class described, the combination with a main operating mechanism, of a bank of keys any two of which may be depressed manually in any order preliminarily to the operation of the machine, means for arresting the keys in their depressed positions, and means for causing further depression of one of said depressed keys, the key further depressed being dependent upon the order of manual depression. 120

36. In a machine of the class described, the combination with a main operating mechanism, of a bank of keys any two of which may be depressed manually in any order preliminarily to the operation of the machine, means for arresting the keys in their depressed positions, and means for causing upon operation of the machine further depression of one of said depressed keys, the key further depressed being dependent upon the order of manual depression. 65
37. In a machine of the class described, the combination with a main operating mechanism, of a bank of keys any two of which may be depressed manually in any order preliminarily to the operation of the machine, the keys being depressible to different positions, means for arresting the keys in their depressed positions, and means for causing further depression of the key which was manually depressed further. 70
38. In a machine of the class described, the combination with a bank of depressible keys any two of which may be depressed in any order, of a detent having two series of grooves, the grooves being so constructed that upon depression of the first key of two depressed keys it coöperates with a corresponding groove in one of said series to arrest the key and raise the detent so that the grooves of the second series are in co-operative relation with the keys, the grooves of the second series being constructed to move the detent further and lock the second depressed key in depressed position. 75
39. In a machine of the class described, the combination with a bank of depressible keys any two of which may be depressed in any order, of a detent having two series of grooves, the grooves being so constructed that upon depression of the first key of two depressed keys it coöperates with a corresponding groove in one of said series to arrest the key and raise the detent so that the grooves of the second series are in co-operative relation with the keys, the grooves of the series being constructed to move the detent further and lock the second depressed key in depressed position, in which position the second depressed key is not depressed to the same extent as the first depressed key. 80
40. In a machine of the class described, the combination with a bank of depressible keys any two of which may be depressed in any order, of a detent having two series of grooves, the grooves being so constructed that upon depression of the first key of two depressed keys it coöperates with a corresponding groove in one of said series to arrest the key and raise the detent so that the grooves of the second series are in co-operative relation with the keys, the grooves of the series being constructed to move the de- 85
- tent further upon operation of the second depressed key and lock the latter in depressed position, and means controlled by said detent for automatically depressing the first depressed key still further. 90
41. In a machine of the class described, the combination with a bank of keys manually depressible to different positions, and a member moved by the keys and having grooves coöperating with said keys for controlling the extent of depression of the keys. 95
42. In a machine of the class described, the combination with a main operating mechanism, of a bank of keys manually depressible to different positions, any two of said keys being depressible preliminarily to the operation of the machine, detent means moved by the keys and having grooves for arresting the keys and for controlling the extent of depression of the latter, means operated by the main operating mechanism for depressing one of the manually depressed keys still further, means for retaining said detent means in arresting position, and means operated by the operating mechanism for disabling said retaining means. 100
43. In a machine of the class described, the combination with a main operating mechanism, of a bank of keys any two of which may be depressed manually in any order preliminarily to the operation of the machine, means for arresting the keys in their depressed positions, and for locking undepressed keys against operation after two keys have been depressed, and means for causing further depression of one of said depressed keys, the key further depressed being dependent upon the order of manual depression. 105
44. In a machine of the class described, the combination with a main operating mechanism, of a bank of keys one or two of which are capable of being depressed preliminarily to the operation of the machine, means for arresting the keys in their depressed positions and for locking undepressed keys against depression after two keys have been depressed, and means for causing upon operation of the machine further depression of one key if two keys have been depressed. 110
45. In a machine of the class described, the combination with a bank of depressible keys any two of which may be depressed in any order, of a detent having two series of grooves, the grooves being so constructed that upon depression of the first key of two depressed keys it coöperates with a corresponding groove in one of said series to arrest the key and raise the detent so that the grooves of the second series are in co-operative relation with the keys, the grooves of the second series being constructed to depress the detent further and lock the second 115
- 120
- 125

depressed key in depressed position and the detent also being constructed to lock undepressed keys against depression after two keys have been depressed.

5 46. In a machine of the class described, the combination with a bank of keys manually depressible to different positions, and a member moved by the keys and having grooves for controlling the extent of depression of the keys, the member being also constructed to lock all but a certain number of keys against depression.

10 47. In a machine of the class described, the combination with a main operating mechanism, of a bank of depressible and arrestable keys, each key representing a digit in a plurality of denominations, accounting means representing the same denominations, and differential means for 15 actuating the accounting means upon operation of the machine and under the control of the bank of keys.

20 48. In a machine of the class described, the combination with a main operating mechanism, of accounting means representing a plurality of denominations, differential means for operating the accounting means, driving means for the differential means, latch means for coupling the driving 25 means and differential means, a bank of depressible and arrestable keys, each key representing a digit in denominations corresponding to those represented by the accounting means, for operating said latch 30 means and thereby control the accounting means.

25 49. In a machine of the class described, the combination with a main operating mechanism, of accounting means representing a plurality of denominations, differential means for operating the accounting means, driving means for the differential means, a plurality of latching mechanisms 35 for coupling the driving means and differential means, a bank of depressible and arrestable keys, representing denominations corresponding to those represented by the 40

accounting means, for operating said latching mechanisms and thereby control the accounting means. 50

5 50. In a machine of the class described, the combination with a main operating mechanism, of accounting means representing a plurality of denominations, differential means for operating the accounting 55 means, driving means for the differential means, latch means for coupling the driving means and differential means, a bank of depressible keys arrestable in different positions and representing denominations corresponding to those represented by the accounting means, for operating said latch 60 means and thereby control the accounting means.

51. In a machine of the class described, the combination with a main operating mechanism, of a bank of depressible and arrestable keys, one or two of which may be depressed preliminarily to the operation 65 of the machine, and two differential mechanisms constructed to be moved to similar extents under the control of a single depressed key and to different extents under the control of two depressed keys. 70

52. In a machine of the class described, the combination with a main operating mechanism, of a bank of depressible and arrestable keys, one or two of which may be depressed preliminarily to the operation 75 of the machine, and two differential mechanisms constructed to be moved to similar extents under the control of a single depressed key and to different extents under the control of two depressed keys, one differential mechanism being controlled always 80 by the first depressed key and the other differential mechanism by the second depressed key. 85

In testimony whereof I affix my signature in the presence of two witnesses.

EDWARD J. VON REIN.
